CLAIM

(57) The ornamental design for a grate spatula, as shown and described.

DESCRIPTION

FIG. 1 is an upper right perspective of a grate spatula showing my new design.

FIG. 2 is a front elevation view thereof.

FIG. 3 is a rear elevation view thereof.

FIG. 4 is a top plan view thereof.

FIG. 5 is bottom plan thereof.

FIG. 6 is a right side elevation view thereof, the left side elevation view being a mirror image.

FIG. 7 is an upper right perspective of a second embodiment of a grate spatula showing my new design.

FIG. 8 is a front elevation view thereof.

FIG. 9 is a rear elevation view thereof.

FIG. 10 is a top plan view thereof.

FIG. 11 is bottom plan thereof; and,

FIG. 12 is a right side elevation view thereof, the left side elevation view being a mirror image.
